DOUBLE-ACTING WOOD WOOL MACHINE

Ernst Alarik Allan Humelin, Tammerfors, Finland

Application July 8, 1949, Serial No. 103,621
In Sweden June 2, 1947

10 Claims. (Cl. 144—185)

1

It is a known fact that wood-wool machines for the production of excelsior having a forward and backward slide the blades are so arranged that the planing of one and the same piece of wood occurs in one movement direction only.

The invention in question concerns a wood-wool machine in which the planing of one and the same piece of wood occurs in both movement directions of the slide by means of double or multi-double blades and a lancet block. The machine is principally characterized thereby that during its running the blades systematically change their position in connection to the to and fro movement of the slide of the machine. These blades are fixed to a separate frame or blade-holder—loosely attached to the slide of the machine—which is so arranged as to obtain its systematic secondary movement by means of the connecting rod that gives the slide its to and fro movement.

The attached drawing illustrates a wood-wool machine according to the invention in question. Fig. 1 shows the schematic wood-wool machine in section, seen from the side. Fig. 2 shows the position of the feeder screws seen from above. Fig. 3 shows a cutting of a feeder screw that illustrates the shape of the threads. Fig. 4 shows the screw and worm wheels seen from the right side. Fig. 5 shows the mantle surface of the screw wheel, cut along the line A—A in Figure 1 and developed on a horizontal level. Fig. 6 shows a modification of the construction according to Figure 1 and Figure 7 also a modification of Figure 1, but with vertical cutting blades from above and Figure 8 a cutting along the line B—B in Figure 7.

In the different figures 1 is a connecting rod that puts slide 2—directed by prisms 3 and 4—into a to and fro movement. The eccentric 5 swings with the connecting rod and alternately presses against rollers 6 and 7, whereat rod 8 glides to and fro in the bearings fixed to the slide or the prisms 9 and 10. Rod 8 has a U-shaped end which encircles crank pin 11, which in turn is mounted on a disk 12 to systematically twist this disc forward and backward whereby the pin 13 gives the frame or blade-holder 14 such a movement that then, for instance, the planing blade 15 rises while the blade 16 placed on the opposite side will lower itself; on the reverse stroke, blade 15 will rise and blade 16 will be lowered, thus permitting planing in both movement directions. The so-called lancet blades 17 are for cutting notches in the wood so that there will be several narrow shavings instead one broad

2

one. The blade-holder is at its other end loosely attached to the axis 18, which is eccentrically placed in connection to the pin 13. In order that the blade-holder should have a better steering both the ends of the axis 18 are of square cross-sectional shape; alternatively a bushing can be used. When changing the blade-holder the pin 13 is removed making it possible to swing the blade-holder around the axis 18, like a door on its hinges, and it can then be easily extracted. Naturally, the blade-holder can be fixed at both ends in a similar manner but in such a case it is more difficult to change the blade-holder. The screws 19, that feed the wood towards the planing blades, obtain their periodic movement via the toothed wheels 20 and 21 in such a manner that the toothed wheels 21, which are fixed at the axis 22, obtain their movement from a driving or work wheel 24 over the shaft 23. The worm wheel 25 having a worm segment 26 each give an impulse per revolution to the geared wheel 24, which thereby obtains an impulse at the end of every stroke of the frame 14, or two impulses per revolution. The cog back 27 situated between the worm segment 26 and the partly double-tracked cog back 28, all of which are without pitch, are there in order to keep the worm wheel in gear between the strokes. In order to be able and utilize the least possible pitch, and thereby provide noiseless running with little wear and tear and at the same time avoid a weakening deformation for the cogs, the worm segments 26 are provided with a small pitch so that each of them only feed the worm wheel half the distance between two cogs. Only after both the screw segments 26 have operated in their turn has the worm wheel 24 twisted a distance equal to that between two cogs. When the gear wheel 24 has rotated a revolution the number of impulses is thus double the number of cogs on the wheel. For instance, if the number of screw segments is increased to three then the number of the impulses is increased to three times that of the cogs. In order to obtain the best possible feeding of the wood the screw threads 19 are so constructed that the side of the thread profile (Fig. 3), which is turned toward the plane, is parallel to the planing surface of the slide. It can be of advantage that there are more screws 19 at each of the piece of wood, thus in two parallel rows (see Fig. 2). In order to steer the wood it is possible to place between the screws, in one of the rows or in both of them, small steering blades 29, in which the edge of the blade is fixed parallelly to the movement direction of the wood.

Giving the screws 19 a somewhat conical shape has the effect that the thread continuously works itself more deeply into the wood, which is thus held in a steady grip.

Fig. 6 illustrates another form of execution that has so to say hanging links, different from those earlier described in which the link was upright with the centre of the disk 12 as a fixed point and the pin 13 located above. In both cases the links can incline towards one or the other side and the angle of inclination can be more or less. The form of the axis 18 can vary and the axis can be firmly attached at the blade-holder or at the slide. The main point is that the connection allows twisting.

It is a common feature for these constructions, which are meant to give the blade-holder the tilting or rocking secondary movement, that the blade-holder is fixed to the slide at two points situated eccentrically in connection to one another.

In the modification according to Figure 6 the blade-holder is loosely fixed to the slide 2 by means of hanging or pendulating links 34 and it obtains its secondary movement from the connecting rod in such a manner that the disk 35, which is firmly attached to the connecting rod 1 and reciprocates with it, has a notch 36 in which is a roller 37 is disposed, which is connected to the blade-holder, whereby the latter, due to the construction of the notch, obtains an impulse at the end of every stroke, in one or the other direction.

The seemingly easiest form of execution, i. e. by mounting the blade-holder in one sole centrally situated axis or in two eccentrically situated axis pins 38, as apparent in Fig. 7, is not as suitable as it seems for the bearing must be placed on both the outer edges of the blade-holder whereby the slide will become considerably broader and the machine thereby larger than at the earlier mentioned construction (Fig. 1) where the bearings are situated so to say behind the planing blades on the inner side of the outer walls of the blade-holder. In these embodiments, the slide is firmly connected at all the corners. In Fig. 7, 39 is a notch that steers a ball 40, fixed to the blade-holder 14. The ball 40 in its turn imparts the tilting movement to the blade-holder.

For clarity's sake I wish to mention that 30 is the crank axis of the machine, 31 the bearings for this axis, 32 is a crank pin, 33 is a bearing pin which simultaneously connects the crank pin 1 to the slide 2 and 41 is the piece of wood that is to be planed.

In all the aforesaid forms of execution the crank pin has even another function than the ordinary task of only giving the slide a to and fro movement and that is that it also imparts to the planing blades the tilting movement executed by them when they, during the running of the machine, change position in connection to the machine's to and fro glide.

It is also possible to arrange several other forms of execution, which belong to the sphere of the invention, and different combinations of those described above within the scope of the claims.

I claim:

1. An apparatus for making excelsior comprising, in combination, slide means; means for reciprocating said slide means; a single, elongated blade holder element pivotally connected at one end portion thereof to said slide means; at least three cutting blades fixedly mounted on said blade holder element, two of said cutting blades being inclined toward each other and con-

verging toward the plane in which said slide means reciprocates and the third cutting blade being located between said two cutting blades and extending in a direction substantially perpendicular to the plane in which said slide means reciprocates; means for turning said blade holder so that only one of said two inclined blades cuts the wood in one direction of movement of said slide means and so that only the other of said two inclined blades cuts the wood in the other direction of movement of said slide means; and means for feeding wood to be cut to said blades.

2. An apparatus for making excelsior comprising, in combination, slide means; means for reciprocating said slide means comprising a connecting rod means pivotally connected at one end thereof to said slide means and pivotally and eccentrically connected at the other end thereof to a rotating drive means; a single, elongated blade holder element pivotally connected at one end portion thereof to said slide means; at least three cutting blades fixedly mounted on said blade holder element, two of said cutting blades being inclined toward each other and converging toward the plane in which said slide means reciprocates and the third cutting blade being located between said two cutting blades and extending in a direction substantially perpendicular to the plane in which said slide means reciprocates; means for turning said blade holder so that only one of said two inclined blades cuts the wood in one direction of movement of said slide means and so that only the other of said two inclined blades cuts the wood in the other direction of movement of said slide means, said means for turning said blade holder comprising a linkage means interconnecting said blade holder and said one end of said connecting rod means for causing the movement of said one end of said connecting rod means to turn said blade holder in opposite directions at the respective ends of the strokes of the connecting rod means; and means for feeding wood to be cut to said blades.

3. An apparatus for making excelsior comprising, in combination, slide means; means for reciprocating said slide means comprising a connecting rod means pivotally connected at one end thereof to said slide means and pivotally and eccentrically connected at the other end thereof to a rotating drive means; a single, elongated blade holder element pivotally connected at one end portion thereof to said slide means; at least three cutting blades fixedly mounted on said blade holder element, two of said cutting blades being inclined toward each other and converging toward the plane in which said slide means reciprocates and the third cutting blade being located between said two cutting blades and extending in a direction substantially perpendicular to the plane in which said slide means reciprocates; means for turning said blade holder so that only one of said two inclined blades cuts the wood in one direction of movement of said slide means and so that only the other of said two inclined blades cuts the wood in the other direction of movement of said slide means, said means for turning said blade holder comprising a bar mounted on said slide means for sliding movement with respect to said slide means in a direction substantially parallel to the plane in which said slide means reciprocates, cam means interconnecting said one end of said connecting rod means and said bar for slidably moving said bar in opposite directions with respect to said slide means at the respective ends of the strokes of said

connecting rod means, a disc rotatably mounted on said slide means, said bar having one end portion thereof pivotally and eccentrically connected to said disc, and said disc being eccentrically and pivotally connected to another end portion of said blade holder, whereby said sliding movement of said bar causes said disc to rotate and tilt said blade holder; and means for feeding wood to be cut to said blades.

4. An apparatus for making excelsior comprising, in combination, slide means; means for reciprocating said slide means; a single elongated blade holder element pivotally connected at one end portion thereof to said slide means; at least three cutting blades fixedly mounted on said blade holder element, two of said cutting blades being inclined toward each other and converging toward the plane in which said slide means reciprocates and the third cutting blade being located between said two cutting blades and extending in a direction substantially perpendicular to the plane in which said slide means reciprocates; means for turning said blade holder so that only one of said two inclined blades cuts the wood in one direction of movement of said slide means and so that only the other of said two inclined blades cuts the wood in the other direction of movement of said slide means; and means for feeding wood to be cut to said blades comprising at least two feeder screws for feeding the wood to be cut and having threads with substantially flat sides confronting said slide means, said flat sides of said threads being located in planes which are substantially parallel to the plane in which said slide means reciprocates.

5. An apparatus for making excelsior comprising, in combination, slide means; means for reciprocating said slide means; a single, elongated blade holder element pivotally connected at one end portion thereof to said slide means; at least three cutting blades fixedly mounted on said blade holder element, two of said cutting blades being inclined toward each other and converging toward the plane in which said slide means reciprocates and the third cutting blade being located between said two cutting blades and extending in a direction substantially perpendicular to the plane in which said slide means reciprocates; means for turning said blade holder so that only one of said two inclined blades cuts the wood in one direction of movement of said slide means and so that only the other of said two inclined blades cuts the wood in the other direction of movement of said slide means; and means for feeding wood to be cut to said blades comprising at least two feeder screws for feeding the wood to be cut and having threads with substantially flat sides confronting said slide means, said flat sides of said threads being located in planes which are substantially parallel to the plane in which said slide means reciprocates and plate means mounted on said apparatus for guiding the wood to be cut and preventing it from turning.

6. An apparatus for making excelsior comprising, in combination, slide means; means for reciprocating said slide means comprising a connecting rod means pivotally connected at one end thereof to said slide means and pivotally and eccentrically connected at the other end thereof to a rotating drive means; a single, elongated blade holder element pivotally connected at one end portion thereof to said slide means; at least three cutting blades fixedly mounted on said blade holder element, two of said cutting blades being inclined toward each other and converging toward the plane in which said slide means reciprocates

and the third cutting blade being located between said two cutting blades and extending in a direction substantially perpendicular to the plane in which said slide means reciprocates; means for turning said blade holder so that only one of said two inclined blades cuts the wood in one direction of movement of said slide means and so that only the other of said two inclined blades cuts the wood in the other direction of movement of said slide means; and means for feeding wood to be cut to said blades comprising at least two feeder screws for feeding the wood to be cut and having threads with substantially flat sides confronting said slide means, said flat sides of said threads being located in planes which are substantially parallel to the plane in which said slide means reciprocates, gear means operatively connected to said feeder screws to rotate the same, and worm means interconnecting said drive means and gear means for rotating said gear means substantially at the ends of the strokes of said connecting rod means and for holding said gear means stationary during movement of said connecting rod means between the ends of its strokes, the extent of rotation of said gear means by said worm means during one revolution of said drive means being substantially equal to the number of degrees occupied by one of the teeth on said gear means.

7. An apparatus for making excelsior comprising, in combination, slide means; means for reciprocating said slide means comprising a connecting rod means pivotally connected at one end thereof to said slide means and pivotally and eccentrically connected at the other end thereof to a rotating drive means; a single, elongated blade holder element pivotally connected at one end portion thereof to said slide means; at least three cutting blades fixedly mounted on said blade holder element, two of said cutting blades being inclined toward each other and converging toward the plane in which said slide means reciprocates and the third cutting blade being located between said two cutting blades and extending in a direction substantially perpendicular to the plane in which said slide means reciprocates; means for turning said blade holder so that only one of said two inclined blades cuts the wood in one direction of movement of said slide means and so that only the other of said two inclined blades cuts the wood in the other direction of movement of said slide means; and means for feeding wood to be cut to said blades comprising at least two feeder screws for feeding the wood to be cut and having threads with substantially flat sides confronting said slide means, said flat sides of said threads being located in planes which are substantially parallel to the plane in which said slide means reciprocates, gear means operatively connected to said feeder screws to rotate the same, and worm means interconnecting said drive means and gear means and having a single thread with a portion thereof located in a plane substantially perpendicular to the axis of rotation of said worm means and extending over slightly less than one-half of the outer surface of said worm means and with additional thread portions connected to the ends of said first-mentioned portion of said worm thread and located on opposite sides of the outer surface of said worm means, the said additional portions of said worm thread being pitched only to the extent that each additional thread portion turns said gear means through approximately one-half of the number of degrees occupied by one of the teeth of said gear means.

8. An apparatus for making excelsior compris-

ing, in combination, slide means; means for reciprocating said slide means comprising a connecting rod means pivotally connected at one end thereof to said slide means and pivotally and eccentrically connected at the other end thereof to a rotating drive means; a single, elongated blade holder element pivotally connected at one end portion thereof to said slide means; at least three cutting blades fixedly mounted on said blade holder, two of said cutting blades being inclined toward each other and converging toward the plane in which said slide means reciprocates and the third cutting blade being located between said two cutting blades and extending in a direction substantially perpendicular to the plane in which said slide means reciprocates; means for turning said blade holder so that only one of said two inclined blades cuts the wood in one direction of movement of said slide means and so that only the other of said two inclined blades cuts the wood in the other direction of movement of said slide means, said means for turning said blade holder comprising a bar mounted on said slide means for sliding movement with respect to said slide means in a direction substantially parallel to the plane in which said slide means reciprocates, cam means interconnecting said one end of said connecting rod means and said bar for slidably moving said bar in opposite directions with respect to said slide means at the respective ends of the strokes of said connecting rod means, a disc rotatably mounted on said slide means, said bar having one end portion thereof pivotally and eccentrically connected to said disc, and said disc being eccentrically and pivotally connected to another end portion of said blade holder, whereby said sliding movement of said bar causes said disc to rotate and tilt said blade holder; and means for feeding the wood to be cut to said blades comprising at least two feeder screws for feeding the wood to be cut and having threads with substantially flat sides confronting said slide means, said flat sides of said threads being located in planes which are substantially parallel to the plane in which said slide means reciprocates, plate means mounted on said apparatus for guiding the wood to be cut and preventing it from turning, gear means operatively connected to said feeder screws to rotate the same, and worm means interconnecting said drive

means and gear means and having a single thread with a portion thereof located in a plane substantially perpendicular to the axis of rotation of said worm means and extending over slightly less than one-half of the outer surface of said worm means and with additional thread portions connected to the ends of said first-mentioned portion of said worm thread and located on opposite sides of the outer surface of said worm means, the said additional portions of said worm thread being pitched only to the extent that each additional thread portion turns said gear means through approximately one-half of the number of degrees occupied by one of the teeth of said gear means.

9. An apparatus as defined in claim 1 and wherein the pivotal connection of said one end portion of said elongated blade holding element to said slide means includes a first elongated link pivoted adjacent one end thereof to said one end portion of said blade holding element and pivoted adjacent the other end thereof to said slide means, said elongated blade holding element having another end portion opposite said one end portion thereof; and a second elongated link pivotally connected adjacent one end thereof to said other end portion of said blade holding element and adjacent the other end thereof to said slide means.

10. Apparatus as defined in claim 1 and wherein the pivotal connection of said one end portion of said elongated blade holding element to said slide means is located in the plane in which said third cutting blade is located.

35 10. Apparatus as defined in claim 1 and wherein the pivotal connection of said one end portion of said elongated blade holding element to said slide means is located in the plane in which said third cutting blade is located.
